CALENDERING, DRYING, OR LIKE TREAT-
MENT OF MATERIALS

William Wycliffe Spooner, Ilkley, England

Application September 8, 1934, Serial No. 743,265
In Great Britain January 30, 1933

9 Claims. (Cl. 34—48)

The present invention relates to the calendering, drying and like treatment of materials such as paper, board or the like.

A method of drying paper, board or like material according to the present invention consists in applying one side of the paper to a heated metallic surface and applying a drying fluid at a temperature higher than that of the paper in the form of a number of high velocity jets directly 5 on to the other side of the paper so as to set up a rapid convectional drying effect in addition to the conductional drying effect of the metallic surface.

Preferably the drying fluid is circulated in a 15 closed path and is projected on to the paper whilst flowing in such closed path.

The fluid is projected on to the paper at an angle thereto, that is not parallel thereto.

The drying fluid may be air, gas, or superheated 20 steam. The metallic surface may be formed by the periphery of a drying cylinder or roll or alternatively it may be formed on one side of a metallic conveyor band preferably an endless conveyor band to which heat is applied on the side remote 25 from the paper. Preferably each jet of fluid extends continuously across the width of the paper and the width at projection may be slightly greater than the width of the paper.

It is advisable to arrange for the projection of 30 the jets of fluid on to the paper to take place within a hood extending over a portion of the path of the paper, so that if desired, the fluid can be drawn by means of a fan from the hood and reprojected in jets on to the paper so as to cause 35 flow of the fluid in a closed path and means may be provided for admitting fresh fluid to the closed path and for rejecting part of the used fluid. Where a hood is employed this may be located adjacent the periphery of a drying roll.

The speed of the fluid may lie between 10 and 40 32 feet per second. Speeds less than 10 feet per second may be employed where it is desired that the drying shall take place at a comparatively slower rate.

A paper-making machine according to the present invention may include one or more cylinders or rolls over which the paper web engages and a casing for the reception of the drying fluid which is located adjacent the path of the paper 50 and has convergent nozzles directed towards the path of the paper for projecting the drying fluid in high velocity jets on to the paper at an angle thereto.

A hood may be arranged over a portion of the 55 paper path to enclose said casing and a fan or

impellor may also be located within the casing. A motor for driving the fan may be mounted on a wall of the casing and may have its axis parallel with the paper web or at right angles thereto.

If desired, the fan may be mounted at some 5 distance from the casing and may be connected thereto by suitable ducts.

Thus, the fan may draw the drying fluid from the hood and may discharge the same to the 10 casing.

A suitable heater may be provided for warming the fluid between the impeller and the said casing. The hood may be hinged about an axis extending widthwise of the casing to enable it together with the casing to be displaced from 15 the paper for inspection purposes.

The invention is very particularly applicable to paper-making machines of the M. G. type in which case the hood is arranged over a portion of the periphery of the drying cylinder. If desired, a single fan and heater and nozzle casing may be arranged within a single hood and a number of such hoods may be provided on a single M. G. cylinder, but alternatively one hood extending over a considerable portion of the 20 periphery of the drying cylinder may enclose a number of fan heater and nozzle casing assemblies, or again a number of nozzle casings located within a single hood may be fed from a single fan through one or more heaters. The 25 hood may completely enclose the fan, heater and casing, but in the case where air is employed as the drying fluid an opening or openings may be provided in the casing to permit admission of fresh air to the hood and for the discharge of 30 used air.

The invention may also be applied to the cylinders of a Fourdrinier machine where the paper is not covered by felts and if desired the fluid may be projected on to the paper in a region 40 where it forms a pocket as it passes over three consecutive rolls or cylinders having their axes triangularly disposed.

One form of construction according to the invention as applied to an M. G. cylinder is shown 45 in the accompanying drawings in which:—

Figure 1 is a front elevation with half of the hood removed.

Figure 2 is a side sectional view on the line A—A of Figure 1 but showing only part of the 50 drying cylinder.

Figure 3 is a sectional view on the line B—B of Figure 2.

A hood 1 whose side walls are built up of plates 55 2 extends over a portion of the periphery of a

drying cylinder 3, and is hingedly mounted and supported through a hinge 4 by bracket members 5. A fan 6 located within the casing and driven by a motor 7 is connected through a duct 8 with 5 a heater 9, the duct 8 having guide plates or vanes 10 at its end near the heater for the purpose of distributing the drying fluid substantially uniformly through the heater. The heater is connected to a casing 11 having two sets of velocity nozzles 12, 13 formed in its face the nozzles 12, 13 being inclined at an angle towards the paper and directed towards one another, that is towards 10 the centre of the casing.

It will be appreciated that the drying fluid in 15 the arrangement shown in the drawings will circulate from the fan through the duct 8 to the heater 9 through the casing 11 and nozzles 12, 13 on to the paper, and thence into the hood, and back to the fan. An outlet for the discharge 20 of part of the drying fluid in circuit is provided at 14 and controlled by a valve 15 shown diagrammatically.

Means not shown are provided for supplying 25 fresh fluid to the circuit and the fresh fluid may be supplied either directly to the heater or to the eye of the fan. If desired, the fan may be provided with an additional set of plates located nearer to the motor than the rotor shown in the drawings for the purpose of drawing in extra 30 fluid. The heater is preferably fed with steam by an inlet 16 the outlet from the heater being shown at 17.

In the arrangement shown in the drawings the 35 motor 7 is secured on the top or side wall of the hood, but if desired it may be secured for the sake of convenience in an end wall of the hood, the position of the fan being correspondingly altered.

I declare that what I claim is:—

40 1. A machine for paper making including at least one heated metallic member over which the paper is conveyed, at least one hood extending over a portion of the path of the paper on said metallic member, a casing between said hood and said metallic member having a wall adjacent the path of the paper and having groups of velocity nozzles in said wall, the nozzles of one group being oppositely inclined with respect to the nozzles of an adjacent group, and an impeller 45 adapted to draw drying fluid from said hood and to discharge the fluid to said casing for ejection through said nozzles onto the paper.

50 2. A machine for paper making including at least one drying cylinder over which the paper is conveyed, at least one hood extending over a portion of the path of the paper on said drying cylinder, a casing between said hood and said drying cylinder having a wall adjacent the path of the paper and having groups of velocity nozzles in said wall, the nozzles of one group being oppositely inclined with respect to the nozzles of an adjacent group, and an impeller adapted to draw drying fluid from said hood and to discharge the fluid to said casing for ejection through said nozzles onto the paper.

60 3. A machine for paper making including at least one drying cylinder over which the paper is conveyed, at least one hood extending over a portion of the path of the paper on said drying cylinder, a casing between said hood and said drying cylinder having a wall adjacent the path of the paper, said wall having spaced transverse velocity nozzles projecting therefrom to form transverse passages along said wall between the 70 nozzles, and an impeller adapted to draw drying

fluid from said hood and to discharge the fluid to the casing for ejection through the said nozzles onto the paper, the fluid being adapted to travel along said transverse passages between the nozzles on its return to the impeller.

5 4. A machine for paper making including at least one heated metallic member over which the paper is conveyed, at least one hood extending over a portion of the path of the paper on said metallic member, a casing carried by said hood and having a wall adjacent the paper on said metallic member, velocity nozzles in the said wall of said casing directed toward the paper, an impeller adapted to draw drying fluid from said hood and to discharge the fluid to said casing 15 for ejection through said nozzles onto the paper, a duct leading from said impeller to said casing for conveying the drying fluid, and a heater arranged in said duct for heating the fluid before its entrance into said casing.

20 5. A machine for paper making including at least one heated metallic member over which the paper is conveyed, at least one hood extending over a portion of the path of the paper on said metallic member, a casing carried by said hood 25 and having a wall adjacent the paper on said metallic member, velocity nozzles in the said wall of said casing directed toward the paper, an impeller adapted to draw drying fluid from said hood and to discharge the fluid to said casing 30 for ejection through said nozzles onto the paper, a duct leading from said impeller to said casing for conveying the drying fluid to the casing, a heater arranged in said duct immediately before its entrance to said casing, and distributing plates 35 arranged in said duct in advance of said heater whereby to uniformly distribute the drying fluid over the heater during its passage therethrough.

6. A machine for paper making including at least one heated metallic member over which the 40 paper is conveyed, at least one hood extending over a portion of the path of the paper and hinged to the machine, a casing between said hood and said metallic member having a wall adjacent the paper, velocity nozzles in said wall of said 45 casing directed toward the paper, and an impeller adapted to draw drying fluid from said hood and to discharge the fluid to said casing for ejection through said nozzles onto the paper.

7. A machine for paper making including at 50 least one drying cylinder over which the paper is conveyed, at least one hood extending over a portion of the path of the paper and hinged to the machine about an axis parallel to the axis of said drying cylinder, a casing between said hood 55 and said drying cylinder having a wall adjacent the paper, velocity nozzles in said wall of said casing directed toward the paper, and an impeller adapted to draw drying fluid from said hood and to discharge the fluid to said casing for ejection 60 through said nozzles onto the paper.

8. A machine for paper making including at least one drying cylinder over which the paper is 65 conveyed, at least one hood extending over a portion of the path of the paper on said cylinder and having the edges of the side walls thereof curved to correspond to the curvature of such cylinder, a casing carried by said hood between the side walls thereof and having a similarly curved wall adjacent the path of the paper, velocity nozzles 70 in said wall of said casing directed toward the paper and an impeller adapted to draw drying fluid from said hood and to discharge the fluid to said casing for ejection through said nozzles onto the paper.

9. A machine for paper making including a drying cylinder over which the paper is conveyed, a hood having the side walls thereof curved to correspond to the curvature of said cylinder, said 5 hood being hinged to the machine to permit angular displacement relative thereto, a casing carried by said hood within the side walls thereof and having a curved wall adjacent and parallel to said cylinder, velocity nozzles in said curved 10 wall of said casing directed toward the paper, an impeller carried by said hood and adapted to

draw drying fluid from the hood, a duct located entirely within the hood and leading from said impeller to said casing, distributing plates located in said duct for uniformly distributing the drying fluid passing therethrough, and a heater 5 located in said duct between said distributing plates and said casing whereby the drying fluid is uniformly heated before it passes into said casing.

10 WILLIAM WYCLIFFE SPOONER.
